UNITED STATES PATENT OFFICE.

CHARLES BLESCH, OF NEWPORT, KENTUCKY, ASSIGNOR TO THE CRANE & BREED MANUFACTURING COMPANY, OF CINCINNATI, OHIO, A CORPORATION OF OHIO.

DESIGN FOR A BURIAL-CASKET HANDLE.

46,892.

Specification for Design.

Patented Feb. 2, 1915.

Application filed October 17, 1914. Serial No. 867,252. Term of patent 14 years.

To all whom it may concern:

Be it known that I, CHARLES BLESCH, a citizen of the United States, residing at Newport, in the county of Campbell and State of Kentucky, have invented a new, original, and ornamental Design for Burial-Casket Handles, of which the following is a specification, reference being had to the accompanying drawing, forming part thereof.

My new, original and ornamental design for a burial-casket handle is shown in the

accompanying drawing, in which the figure is a front elevation of a burial-casket handle, showing my new design, one end of the handle-bar being broken away.

I claim:

The ornamental design for a burial-casket handle, substantially as shown.

CHARLES BLESCH.
